Des. 420

William Savery, of New-York, N.Y.
Letters Patent No 420. Dated Oct. 21st 1851.

~~~~~
The schedule referred in these Letters Patent and making
part of the same.

To all whom it may concern:

Be it known that

I, William Savery of the City, County & state of New York have invented a new design for Cook, Stove Plates, and I do hereby declare that the following is a full description of the same, reference being had to the accompanying drawings.— A, represents the front with doors therefor. B, represents the side with oven door therefor when hung.

What I claim as original and wish to secure by letters patent is the design & configuration of the several ornamental figures on the front & side plates and doors of a certain stove, as represented in the annexed drawings, and as above described.
